UNITED STATES PATENT OFFICE.

CYRUS F. GILLETT, OF SPARTA, WISCONSIN.

IMPROVEMENT IN SCRUBBING-BRUSHES.

Specification forming part of Letters Patent No. 129,944, dated July 30, 1872.

SPECIFICATION.

To all whom it may concern:

Be it known that I, CYRUS F. GILLETT, of Sparta, in the county of Monroe and in the State of Wisconsin, have invented an Improved Brush; and do hereby declare that the following description, taken in connection with the accompanying plate of drawing, hereinafter referred to, forms a full and exact specification of the same, wherein I have set forth the nature and principles of my said improvement, by which my invention may be distinguished from others of a similar class, together with such parts as I claim and desire to secure by Letters Patent.

My invention relates to that class of brushes which are made use of for scrubbing; and the nature thereof consists in certain modifications and improvements in the details of the construction of the same, hereinafter described and shown.

In the accompanying plate of drawing, which illustrates my invention and forms a part of this specification—

Figure 1 is a perspective view. Fig. 2 is a transverse section.

The construction of my improved brush may be described as follows: A, of the drawing, represents a series of slats or strips of wood or metal, between which the broom-straw is held in the manner shown. C C represent screw-bolts passing through the ends of the slats A, and respectively secured firmly or made removable by means of the nuts D D. I usually affix a handle to my brush by means of a socket attachment, as represented on the drawing, which is removable or attachable at will; but this method of attaching the handle forms no part of my invention.

I claim as my invention—

The scrubbing-brush herein described, formed by the series of slats or strips of wood or metal, arranged as specified, together with the bolts C and nuts D, and the requisite straw or splints, substantially as shown and described.

In testimony that I claim the foregoing I have hereunto set my hand this 8th day of May, 1871.

CYRUS F. GILLETT.
